Filed Jan. 12, 1973, Ser. No. 323,029

Term of patent 14 years

Int. Cl. D9—01

U.S. Cl. D9—107

FIG. 1 is an elevational view of a combined bottle and cap therefor showing my new design;

FIG. 2 is an elevational view looking from the right of FIG. 1;

FIG. 3 is an elevational view showing the side opposite that seen in FIG. 1.

FIG. 4 is an elevational view looking from the left of FIG. 1; and

FIG. 5 is a top plan view with the cap removed.

The characteristic features of the design reside in the appearance and configuration of the bottle portion.

I claim:

The ornamental design for a combined bottle and cap therefor, as shown.
